US0D1112196S

(12) **United States Design Patent** (10) **Patent No.:** **US D1,112,196 S**
(45) **Date of Patent:** **** Feb. 10, 2026**

(54) **HOLDER FOR CELL PHONES**

(71) Applicant: **motogadget GmbH**, Berlin (DE)

(72) Inventor: **Garrit Keller**, Berlin (DE)

(73) Assignee: **motogadget GmbH**, Berlin (DE)

(**) Term: **15 Years**

(21) Appl. No.: **29/916,910**

(22) Filed: **Nov. 16, 2023**

(30) **Foreign Application Priority Data**

Nov. 6, 2023 (EM) 015040035-0001

(57) **CLAIM**

The ornamental design for a holder for cell phones, as shown and described.

DESCRIPTION

FIG. 1 shows a perspective view of a holder for cell phones according to the present invention;

FIG. 2 shows a front view thereof;

FIG. 3 shows a right side view thereof;

FIG. 4 shows a rear view thereof;

FIG. 5 shows a left side view thereof;

FIG. 6 shows a top view thereof;

FIG. 7 shows a bottom view thereof; and,

FIG. 8 shows another perspective view thereof.

The broken lines used depict portions of the holder for cell phones that form no part of the claim design.

1 Claim, 8 Drawing Sheets
